(57) CLAIM

I claim the ornamental design for a hard-pack snow ski cover, as shown and described herein.

DESCRIPTION

This application is related to U.S. Design patent application Ser. No. 29/760,777.

FIG. 1 is a front to back top perspective view of the hard-pack snow ski cover.

FIG. 2 is a left side view thereof. The right side is a mirror image.

FIG. 3 is a bottom plan view thereof with the front on the left.

FIG. 4 is a front to back bottom perspective view thereof.

FIG. 5 is a front view thereof; and,

FIG. 6 is a back view thereof.
